DESCRIPTION

FIG. 1 is a front elevational view of an antenna showing my new design;

FIG. 2 is a rear elevational view thereof;

FIG. 3 is a partially enlarged front elevational view thereof along the lines 3-3 and 3'-3' of FIG. 1; and,

FIG. 4 is a partially enlarged rear elevational view thereof along the lines 4-4 and 4'-4' of FIG. 2.

The broken lines illustrating the unclaimed portions of the antenna form no part of the claimed design. Dot-dash broken lines forming boundaries of the claimed design form no part of the claimed design.
